UNITED STATES PATENT OFFICE

JOHN ELLIS OSTLINE, THOMAS R. RAYNER, AND THOMAS PHILIP PREIST, OF LIVERPOOL, ENGLAND, ASSIGNEES TO ASSOCIATED TELEPHONE AND TELEGRAPH COMPANY, OF KANSAS CITY, MISSOURI, A CORPORATION OF DELAWARE

TELEPHONE SYSTEM

Application filed November 21, 1927, Serial No. 234,608, and in Great Britain March 2, 1927.

The present invention relates to telephone systems and is more particularly concerned with arrangements for notifying a calling party of the busy condition of a line or group 5 of lines which has been encountered in the setting up of a connection. The problem to be solved is that the signalling condition must be such as to give a tone in case the calling party is a subscriber and also to provide a 10 special current for operating a flashing signal in case the calling party is an operator. This latter requirement has been met by arranging for the alternate connection of battery and earth to one speaking lead through the 15 winding of the line relay and in these circumstances the line relay will release at the time a simplex battery connection is made. Accordingly arrangements must also be provided, conveniently by completing an alternative circuit for the usual release relay, to prevent the connection from being cleared down 20 during this interval. It has also been usual in the past to superimpose the busy tone on the special connection to one speaking lead 25 as this simplifies the circuits and reduces to a minimum the number of common leads required. It is found, however, that when the busy tone is provided in sufficient volume to transverse long junction lines, considerable 30 overhearing or cross talk is apt to occur owing to the fact that the tone is applied to one leg only and hence owing to the various bridges across the line, the return tone current is by no means equal to that originally applied. 35 The present invention aims at overcoming these disadvantages by applying the tone in such a fashion as to secure complete balance at all times and thus eliminating the detrimental effects of overhearing which it will 40 be appreciated might constitute a serious disadvantage.

According to one feature of the invention, this object is attained in that the two speaking leads are adapted to be connected respectively to opposite sides of the busy tone source at the switch at which the busy condition is encountered so that the tone is applied in a loop circuit.

According to another feature of the invention, the busy tone source is adapted to be con-

nected without battery or earth connections across the speaking leads at the switch at which the busy condition is encountered which means that leakage which might give rise to overhearing is almost entirely prevented.

In order that the principles of the invention may be better appreciated, various arrangements for carrying it into effect will now be described by way of example, reference being had to the accompanying drawings.

Fig. 1 shows a well-known arrangement for applying busy tone to a calling line from a connector switch. Fig. 2 shows an arrangement for applying a busy tone to both speaking conductors of a calling line in series. Fig. 3 shows an arrangement for applying a busy tone to both speaking conductors of a line through the windings of the line relay. Fig. 4 shows an arrangement somewhat similar to Fig. 3 except that the tone is applied to the line conductors through resistances instead of through the windings of the line relay. Fig. 5 shows the arrangement of Fig. 1 modified for use with a selector switch. Fig. 6 is a modification of Fig. 2 as applied to a selector switch. Fig. 7 shows an arrangement for applying busy tone to a line through an auxiliary winding of the line relay. Fig. 8 shows another arrangement for applying busy tone to a line from a selector. Fig. 9 is a modification of Fig. 3 showing a method of reducing the number of conductors between the individual switches and the common tone apparatus.

Referring first to Fig. 1 this shows in schematic form one arrangement which is at present employed, this arrangement being open to certain of the objections mentioned above. Reference numeral 1 represents the transmitter as typical of the substation, and 2 is the line relay which supplies feeding current. The high impedance relay 3 is connected across the line in known manner in series with the polarized relay 4 which is used for effecting metering or giving supervisory signals. The line relay of a connector switch is indicated by 5, and 6 is the release relay which is energized over its top wind-

ing when the line relay is operated. In the case of a connector a busy condition will only arise in case the line of the party desired is found busy and in this case contacts 7 and 8 carried by the busy relay will be operated. The equipment enclosed in the dotted rectangle is common to a number of switches and comprises the busy tone transformer BT, and the interrupter relay 11, which is energized and deenergized periodically, for instance every $1\frac{1}{2}$ seconds, by means of the interrupter contact 12. It will be seen that after contacts 7 and 8 are operated and while relay 11 is not operated, battery will be connected to the lower speaking conductor through the lower winding of line relay 5 and battery will also be connected through the lower winding of release relay 6 to maintain this relay operated. When the interrupter contacts 12 next close, relay 11 is operated and thereupon at armature 9 busy tone is connected up and the holding circuit for relay 6 is opened so that if the subscriber hangs up at this time the connection will be released. It will be seen that the busy tone is applied to one lead only and the return circuit may be by way of either relay 2 or relay 5 so that a certain amount of unbalance is produced and overhearing is likely to occur. This can be reduced to some extent by connecting the junction of the winding of relay 5 and the upper speaking lead to earth through a suitable condenser.

In the more completely satisfactory arrangement shown in Fig. 2 however, the trouble is overcome in that the busy tone from the transformer BT is applied to both speaking leads over the operated armatures 16 and 17 of the busy relay. Armatures 15 and 18 carried by this relay performs the same functions as in the arrangement shown in Fig. 1 and as before the interrupter relay 22 operates the armatures 19, 20 and 21. In this case, the busy tone circuit is independent of the circuit over armature 15 by which battery and earth are connected alternately to the lower winding of line relay 14. Each connector is provided with a busy tone condenser 23 which, together with the common busy tone condenser 24, serve to prevent interference between lines connected to the common tone apparatus simultaneously.

In the arrangement according to Fig. 3, the busy tone instead of being applied directly to the speaking leads as in the arrangement shown in Fig. 2 is supplied through both windings of the line relay 23 and the connection of battery to the middle point of the secondary of the transformer BT for the flashing signal ensures that complete balance shall be obtained at all times. It will be understood that armatures 24, 25 and 26 are again carried by the busy relay.

In Fig. 4 a somewhat different arrangement is employed in that busy tone is now

applied to the two speaking conductors through the resistances 31 and 32 which may conveniently have a value of approximately 50 ohms. In this case the line relay 30 is held up during the application of the flash battery owing to the local circuit which is then completed for its lower winding. Consequently since relay 30 does not deenergize at any time there is no necessity for the provision of a holding circuit on the release relay and thus the number of common leads can be reduced.

The problem of giving busy from a selector switch is substantially the same though in this case instead of the necessary circuit changes being effected by a busy relay, they will be brought about by cam springs which are operated when the switch moves to its all trunks busy position. Figure 5 shows diagrammatically an arrangement at present employed for giving busy from a selector, and it will be appreciated that it is substantially the same as that shown in Figure 1 covering the case of a connector. The springs 42 and 43 in Fig. 5 are however cam springs and during the application of busy flash battery, relay 40 is deenergized while release relay 41 is at this time energized over the special holding circuit. As pointed out in connection with Fig. 1 the application of busy tone is in this circuit to one lead only.

The arrangement shown in Fig. 6 is substantially similar to that shown in Fig. 2, though in this case the springs 44, 45, 46 and 47 are cam springs rather than armatures on a relay. Moreover the connection of the leads through which the busy tone is fed will be made not to the actual speaking leads but to the leads extending to the windings of the line relay over back contacts carried by the switching relay since this relay is not operated when the switch moves to the eleventh rotary position. Armatures 48, 49 and 50 are, it will be understood, carried by the interrupter relay, and 51 is the usual release relay for which a holding circuit is completed through its lower winding during the time that busy flash battery is being applied.

A modified arrangement is shown in Fig. 7, the feature of which is that the busy tone is not connected directly to the line or to the normal windings of the line relay but a third winding is provided on the line relay and busy tone is fed through this whence it is transmitted to the calling party by induction. Conveniently the circuit for this third winding of line relay 55 may include the second winding on the release relay 51, conveniently shunted by a condenser 57, but if desired the current flow through the third winding may be arranged to be sufficient to hold the line relay energized during the time that current is cut off through the usual two windings and in this case no second winding is necessary for the release relay since its usual circuit will

be completed the whole time by the line relay. Springs 59 and 60 it will be understood are cam springs operated when the switch moves to the eleventh rotary position. This arrangement may be preferable to that shown in Fig. 6 in that it only requires two common leads as against four required with the latter arrangement.

Figure 8 shows a further modification in which only two common leads are used and holding is effected over one of them which also serves for the application of the busy flash battery. In this case the lower winding of line relay 61 is connected to the associated speaking conductor through the resistance 62 and when the cam springs 63 and 64 are operated, busy tone is connected up to the speaking conductors in a circuit which will be readily followed and when the interrupter relay energizes it applies battery at armature 65 to maintain line relay 61 over its lower winding. In this case the interrupter relay also at armature 66 disconnects the busy tone by opening the primary winding of the busy tone transformer this arrangement being preferable in some cases.

Figure 9 shows a further modification of Fig. 3 in which only two common leads are used and the holding is effected over one of the common leads. In this case the busy tone is connected directly to the two speaking leads through the contacts 68 and 69 controlled by the busy relay and the battery potential connected to the middle point of the secondary winding of the busy transformer BT maintains the line relay 67 energized.

It will be seen therefore that according to the invention various novel and improved arrangements have been devised for feeding busy tone in a balanced circuit while at the same time providing facilities for flashing the supervisory lamp at an operator's position and preventing any appreciable degree of overhearing.

What is claimed is:

1. In a telephone system including automatic switches for setting up connections between a calling and a called line, a busy tone source, and means operative when a busy line or group of lines is encountered in setting up a connection for connecting the busy tone source without battery or ground connections across the speaking leads at the switch at which the busy condition is encountered to transmit the busy tone to the calling line.

2. In a telephone system including automatic switches for setting up connections between a calling line and a called line, a busy tone source and a special signalling current, and means operative when a busy line or group of lines is encountered by one of said switches in setting up a connection for transmitting the special signalling current in the direction of the calling line and for connecting the two speaking leads of the switch, re-

spectively, to opposite sides of the busy tone source to transmit a busy tone to the calling line.

3. In a telephone system as claimed in claim 2, in which the busy tone source and special signalling current are applied simultaneously but alternate with normal conditions.

4. In a telephone system including automatic switches for setting up connections between calling and called lines, a busy tone source and a special signalling current, and means operative when a busy line or group of lines is encountered by one of said switches in setting up a connection for connecting the special signalling current through a winding of the line relay of said switch and for connecting the busy tone source directly to the two speaking leads of said switch.

5. In a telephone system, an automatic switch for extending connections between calling and called lines, a line relay and a release relay in said switch, a busy tone source and a special signalling current, means operative when a busy line or group of lines is encountered by said switch in setting up a connection for connecting said busy tone source to the two speaking leads of said switch and for connecting said signalling current to a winding of said line relay, and means comprising a special holding circuit for said release relay to prevent the release of said switch in case the line relay deenergizes when said signalling current is connected thereto.

6. In a telephone system including automatic switches for setting up connections between a calling line and a called line, a busy tone source and a special signalling current, and means responsive when a busy line or group of lines is encountered by one of said switches for transmitting the special signalling current in the direction of the calling line and for transmitting the busy tone from said source over the two talking conductors of the switch in series.

7. In a telephone system, an automatic switch for extending connections between calling and called lines, a release relay in said switch, a busy tone source and a special signalling current, means responsive when a busy line or group of lines is encountered by said switch in setting up a connection for applying the busy tone from said source to the two talking conductors of said switch and for transmitting the special signalling current in the direction of the calling line, and means for maintaining said release relay energized during the transmission of said special signalling current.

8. In a telephone system including automatic switches for setting up connections between calling and called lines, a busy tone source comprising a transformer common to all said switches, a condenser individual to

- each of said switches and another condenser common to all of said switches, and means responsive when a busy line or group of lines is encountered by one of said switches for connecting the secondary winding of said transformer to the talking conductors of the switch in series with said condensers.
9. In a telephone system including automatic switches for setting up connections between calling and called lines, a busy tone source comprising a transformer common to all of said switches, a condenser common to all of said switches and a non-talking condenser individual to each of said switches, and means responsive when a busy line or group of lines is encountered by one of said switches for connecting the secondary winding of said transformer to the calling line in series with said condensers.
10. In a telephone system, a line comprising two conductors terminating in an automatic switch, a double-wound line relay for the switch normally bridged across the conductors of said line in series with battery and ground, a busy tone transformer, and means for intermittently bridging said transformer across the conductors of said line and for substituting a battery connection for the normal ground connection in first said bridge.
11. In a telephone system, an automatic switch including a double-wound line relay for extending connections to called lines, a bridge including a busy tone transformer connected across the talking conductors of the switch responsive to the extension of a connection to a busy line, and an interrupter relay for alternately connecting ground and battery to a winding of the line relay and for alternately opening and closing said bridge.
12. In a telephone system including automatic switches for setting up connections between calling and called lines, a double-wound line relay for each switch, a common busy tone source, and means operative when a busy line is encountered by one of said switches for alternately connecting battery and ground to a winding of the line relay of the switch and for connecting said busy tone source across the talking conductors to the switch.
13. In a telephone system including automatic switches for setting up connections between calling and called lines, a line relay and a release relay for each switch, a common busy tone source, and means operative when a busy line is connected with by one of said switches for alternately connecting battery and ground to a winding of the line relay of the switch, for connecting said busy tone source across the talking conductors of the switch, and for intermittently completing an auxiliary holding circuit for the release relay of the switch.
14. In a telephone system including automatic switches for extending connections be-
- tween calling and called lines, a line relay for each switch, a busy tone source common to all of said switches, means operative when a busy line is connected with by one of said switches for connecting said tone source in bridge of the talking conductors of the switch, and an interrupter relay for intermittently opening and closing said bridge, and for alternately connecting battery and ground to a winding of the line relay of the switch.
15. In a telephone system, an automatic switch for extending a connection between calling and called lines, a line relay in said switch having two windings connected to the two speaking leads of said switch and having an auxiliary winding, a busy tone source, and means operative when a busy line or group of lines is encountered by said switch in extending a connection for connecting said source to said auxiliary winding, said auxiliary winding inductively causing a busy tone to be transmitted in the direction of the calling line through the other windings of said line relay.
16. In a telephone system, an automatic switch for extending a connection between calling and called lines, a line relay in said switch having two windings connected to the two speaking leads of said switch and having an auxiliary winding, a busy tone source, and means operative when a busy line or group of lines is encountered by said switch in extending a connection for connecting said source to said auxiliary winding, said auxiliary winding inductively causing a busy tone to be transmitted in the direction of the calling line through the other windings of main line relay, and for maintaining said line relay energized independent of the calling line.
17. In a telephone system as claimed in claim 15 including a release relay for said switch in which the busy tone source is also fed through a winding on the release relay.
18. In a telephone system, an automatic switch for extending connections between calling and called lines, a line relay in said switch having two windings, one or more resistances in said switch, the two speaking conductors of said switch connected to the two windings of said relay, respectively, by way of one or more of said resistances, a busy tone source, and means operative when said switch encounters a busy line or group of lines for connecting said busy source directly to the windings of said relay and to the two speaking leads by way of one or more resistances in order to transmit a busy tone to the calling line.
19. In a telephone system, an automatic switch for extending connections between calling and called lines, a line relay in said switch having two windings, one or more resistances in said switch, the two speaking conductors of said switch connected to the two

windings of said relay, respectively, by way of one or more of said resistances, a busy tone source, means operative when said switch encounters a busy line or group of lines for connecting said busy source directly to the windings of said relay and to the two speaking leads by way of one or more resistances in order to transmit a busy tone to the calling line, and a special signalling current connected directly to one winding of said line relay and to one speaking conductor alternately with said busy tone source in order to transmit signalling current toward the calling line.

20. In a telephone system including automatic switches for setting up connections between calling and called lines, a busy tone source and a special signalling current, and means operative when a busy line or group of lines is encountered by one of said switches 15 in setting up a connection for connecting the busy tone source to the two speaking leads of said switch and for connecting the special signalling current in the direction of the conductors of said switch and to transmit the 20 signalling current in the direction of the calling line.
